(57) **CLAIM**

The ornamental design for a vehicle headlight lens, as shown and described

DESCRIPTION

FIG. 1 is a frontal perspective view of a left headlight lens attached to a vehicle, no part of the vehicle is claimed;

FIG. 2 is a perspective view of the left headlight lens;

FIG. 3 is a front elevation view of the left headlight lens;

FIG. 4 is a top plan view of the left headlight lens;

FIG. 5 is a right side elevation view of the left headlight lens;

FIG. 6 is a left side view of the left headlight lens;

FIG. 7 is a bottom view of the left headlight lens;

FIG. 8 is a front elevational view of a vehicle headlight lens illustrated in FIGS. 1-7, showing a right vehicle headlight lens, with the vehicle shown in broken lines and forming no part of the claimed design;

FIG. 9 is a perspective view of the right headlight lens;

FIG. 10 is a front elevation view of the right headlight lens;

FIG. 11 is a top plan view of the right headlight lens;

FIG. 12 is a left side elevation view of the right headlight lens;

FIG. 13 is a right side view of the right headlight lens; and, FIG. 14 is a bottom view of the right headlight lens.

The phantom lines are not a part of the claimed invention.

The stippling indicates the curvature of the headlight lens. The headlight lens has a broad frontal profile and a thinner side profile.
